UNITED STATES PATENT OFFICE.

GEORGE H. FORSYTH, OF SAN MATEO, CALIFORNIA, ASSIGNOR TO STEEL WHEEL CORPORATION, OF LANSING, MICHIGAN, A CORPORATION OF MICHIGAN.

DISK WHEEL.

Original application filed March 24, 1922, Serial No. 546,272. Divided and this application filed September 30, 1925. Serial No. 59,471.

This application is a division of my co-pending application Serial No. 546,272 filed March 24, 1922.

This invention has for its primary object the adaptation of a disk wheel for the provision of strength, resiliency, pleasing contour and convenience of assembly of the hub, disk, body and rim, together with ease of access to the usual straight valve stem of the tire for inflating without impairing these features of the wheel.

It is recognized that a dished disk, preferably reversely curved in radial section, has greater resistance as a wheel body to both diametric and lateral strains and also greater capacity for recovery from deformation than has a flat disk whether disposed parallel to the wheel plane or at an inclination.

The employment of a disk of such curvature to the hub and rim in such relation as to conserve the important qualities of resiliency, strength, resistance to diametric and lateral stresses and recovery from deformation introduces difficulty by way of interference between the disk and the usual valve stem, and many expedients have been resorted to for overcoming or minimizing the same, such as, for instance, providing deep pockets in the wheel face and housing therein a horizontally projecting angular valve stem, aperturing the disk and projecting the valve stem therethrough, disposing the valve stem at an inclination to the wheel plane, etc.

My invention provides access from the front of the wheel to a straight valve stem disposed in the wheel plane without materially altering the disk contour and without weakening the same by slotting or perforating the disk inwardly of the rim while utilizing a dished disk of reversely curved radial section.

The invention also presents the advantage of capacity for lateral withdrawal of the rim, tire and valve stem from the wheel without necessity of lifting the same axially to free the stem from the disk, and the pro-

tection of the valve stem by the overlying rim-retaining element at the front of the wheel.

Another feature is the subjecting of the disk to radial compressive stress by means of lateral deformation in the hub zone.

Other advantages of the invention, whether embodied in a wheel equipped with demountable rim, or with fixed rim and demountable at the hub will be apparent to those skilled in the art.

In order that the invention may be readily understood and appreciated, I have illustrated the same in the accompanying drawings as embodied in two disk wheels of different contour and in the accompanying description based upon such illustrations have set forth the detailed features of such embodiments. It is to be understood, however, that these two examples are given by way of exemplification only and the invention is not to be construed as limited thereby.

In the drawings—

Figs. 1 and 2 are radial sections through disk wheels of slightly different contour illustrating the embodiment of the invention therein.

Having particular reference to Fig. 1 of the drawing the pressed steel hub 11 having an integral rear radially projecting flange 12 is assembled by means of the removable front flange or plate 13 and the bolts 14 with the single dished disk 15. It will be observed that the curvature of the central portion of the disk lying adjacent the flange 12 is slightly different from that of the flange 12 at the point 16 with the result that as the hub flanges and disk are assembled contact is first obtained at 17 near the periphery of the flange 12 whereby the tightening of the bolts 14 serves to radially stress the disk body and to insure a firm bearing support for the disk at the point 17.

Outwardly beyond the hub connection the disk curves to the rear and again to the front presenting a forwardly concave surface in its medial or body portion, with a

forwardly projecting shoulder or bead 18 whence the disk extends in its peripheral portion radially and then rearwardly at 19 to an inclined marginal portion 20 which 5 constitutes a rear support for the rim 21, in this case shown as demountable. The forward edge of the rim 21 is supported by a rim-retaining member 22 here shown as a ring, although as an equivalent construction 10 individual separated clips or other rim-retaining means may be employed. The ring 22 has its inner portion fulcrumed at 23 upon the shoulder 18 of the disk 15.

At a point corresponding to the location of the valve stem 24 the rim-retaining ring 22 is notched at 25 and the valve stem 24 extends through said notch and is closed by the cap 26 which bears at its upper edge upon the lower horizontal portion of the 20 ring about the notch.

In Fig. 2 of the drawing the cast or forged hub 27 is of similar construction being provided with the integral flange 28 and the removable flange or plate 29 between which 25 the central portion of the disk 30 is clamped by the bolts 31. As in the former case, the central portion of the disk and of the flanges is preferably such as to secure intimate firm contact at the point 32. Here the disk extends rearwardly and again forwardly to present the concave intermediate or body portion provided with a bead or shoulder 33 and thence extends in its peripheral portion radially and rearwardly to the inclined 30 supporting margin 34. As in the former case the rim 21 is supported at its front edge by the rim-retaining element 35, here shown as a ring fulcrumed at its inner edge 36 upon the beaded portion 33 of the disk.

40 In this form of construction it will be observed that that portion of the disk adjacent the valve stem 24 extends forwardly across the median plane of impact of the wheel and thus forwardly beyond the valve 45 stem, the axis of which normally coincides with such median plane. This is true throughout the disk except at the point where the valve stem is located. Here the disk is radially recessed as illustrated at 37 and the valve stem lies within such recess, its lower end covered by the cap 38 extending inwardly for a considerable distance.

As shown in both Figs. 1 and 2, it will be 55 observed that, as distinguished from a radially corrugated disk, the front contour of the disk body is plain, having a front surface generated by the revolution about the wheel axis of a line angularly projected therefrom, whether such line be straight or 60 curved in the plane of the wheel axis.

In Fig. 1 it will be seen that each portion 65 of the disk 15 is at the rear of the median plane of wheel impact, while in Fig. 2 the central and peripheral portions of the disk extend across the median plane of impact

to the front thereof. In the former case the retaining ring is recessed to enclose the valve stem, whereas in the latter case the disk is itself recessed to accommodate the valve stem. In neither case is the disk weakened 70 by perforating or slotting the same to accommodate the valve stem, and yet the valve stem is brought to the front of the disk and is made readily accessible for inflating purposes.

75 It will be seen that throughout that portion of the valve stem adjacent the rim, where most subject to injury from bad roads, stones and the like, the rim-retaining element overlies the valve stem as a protective covering while leaving the inner inflation end accessible for inflation.

80 It will also be observed that whether the tire carrying the valve stem is to be removed from a fixed rim as in case of needed repair or whether a demountable rim carrying the tire is to be removed from the wheel, in either case after the removal of the rim-retaining ring or clips the tire can be withdrawn from the wheel laterally without the necessity of lifting the valve stem radially out of an aperture of the disk or from behind an imperforate disk.

85 Thus the employment of a straight valve stem in connection with a perforate disk of the reversely curved type, is made compatible with accessibility of the valve stem for inflation from the front and associated with the feature of ready withdrawal laterally.

90 I claim:

1. In a disk wheel, the combination of a central hub portion, a peripheral tire-carrying portion, and an intermediate disk body portion, the wheel provided at the hub with a radially projecting disk supporting member, and means to clamp the disk to the supporting member, the contour of the overlapping portions of the disk and supporting member being diverse to the extent that when forced together the disk will first contact the 100 peripheral portion of the support and be slightly deformed to effect and maintain a tight fit under stress.

105 2. In a wheel, the combination of a central hub portion, a peripheral tire-carrying portion, and an intermediate disk body portion, the wheel provided at the hub with a radially projecting disk supporting member, the contour of the overlapping portions of the disk and supporting member being diverse to the extent that when forced together the disk will first contact the peripheral portion of the support and be slightly deformed to effect and maintain a tight fit 110 and to place the body portion of the disk 115 under stress radially applied.

120 3. In a wheel, the combination of a central hub portion, a peripheral tire-carrying portion, and an intermediate disk body portion, the disk body at the hub clamped be- 125

tween front and rear supporting members projecting radially from the hub proper into overlapping relation with the disk, the contour of the overlapping disk and supporting members being diverse to the extent that when forced together the disk will first contact with the peripheral portions of the

supporting members and be slightly deformed to effect and maintain a tight fit under stress.

In testimony whereof I have hereunto signed my name.

GEORGE H. FORSYTH.
